UNITED STATES PATENT OFFICE.

CLARK E. SULLIVAN, OF GRAND RAPIDS, MICHIGAN.

WRENCH.

1,172,319.

Specification of Letters Patent. Patented Feb. 22, 1916.

Application filed July 2, 1915. Serial No. 37,738.

To all whom it may concern:

Be it known that I, CLARK E. SULLIVAN, a citizen of the United States, residing at Grand Rapids, in the county of Kent and 5 State of Michigan, have invented certain new and useful Improvements in Wrenches; and I do hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to new and useful improvements in nut wrenches and consists essentially in the provision of a sliding jaw wrench, actuated by means of a rack and pinion and in the provision of an adjusting 20 screw.

The invention consists further in the provision of a self-adjusting wrench of this nature having various details of construction, combinations and arrangements of parts 25 which will be hereinafter fully described, shown in the accompanying drawings and then specifically defined in the appended claims.

My invention is illustrated in the accompanying drawings, in which:

Figure 1 is a side elevation of the wrench, parts being broken away to better illustrate features of the invention. Fig. 2 is a view showing the wrench partly closed.

35 Reference now being had to the details of the drawings by letter, A designates one jaw which has a slot B therein for the reception of the shank portion D of the sliding jaw E, said shank portion having teeth F upon one 40 edge. A pivotal pin H passes through registering slots in the jaw A and upon this pin H the head K of the handle K' is pivoted, said head having circumferential rack teeth which are in engagement with the rack teeth 45 upon the shank portion of jaw E. An extension A' has a convexed milled edge A² against which a thumb may bear for the purpose of ready and convenient adjustment of the jaw by the thumb of the hand gripping 50 the handle.

Mounted within the chamber of the shank portion of the wrench is a coiled spring L bearing against the bottom of the recess in which it is mounted and the edge of the head

of said handle and serves as a friction means 55 to prevent the jaws striking together. Teeth I are formed upon the opposite edges of the handle and an interiorly threaded ring N is mounted upon said threaded portion, its movement in one direction being 60 limited by the pin O.

The operation of my invention will be readily understood and is as follows: When a person grips the handle, the thumb of the operator may conveniently engage the milled 65 edge of the projection of the jaw, allowing the two jaws to be moved toward or away from each other and, when in adjusted positions, the interiorly threaded ring may be secured upon the handle to hold the jaws in 70 proper adjustment.

What I claim to be new is:—

1. A wrench comprising a jaw with a chambered portion, a handle with a head pivoted within the chamber of the jaw and 75 having teeth upon the end thereof, a second jaw with a shank portion movable through a slot in the chambered jaw and having teeth upon one edge for engagement with the teeth at the end of said handle, and a 80 thumb projecting upon the chambered jaw forming means whereby the jaws may be adjusted, and means for holding the jaws in adjusted positions.

2. A wrench comprising a jaw with a 85 chambered portion, a handle with a head pivoted within the chamber of the jaw and having teeth upon the end thereof, a second jaw with a shank portion movable through a slot in the chambered jaw and having 90 teeth upon one edge for engagement with the teeth at the end of said handle, a thumb projecting upon the chambered jaw forming means whereby the jaws may be adjusted, a handle of the jaw of the wrench having 95 threads, and an interiorly threaded ring engaging the threads upon the handle and adapted to bear against the projection of the chambered jaw to hold the two jaws in adjusted positions.

3. A wrench comprising a chambered jaw with a lateral projection, convexed upon its edge and milled, a pivotal pin passing through the chambered portion of the wrench, a handle with a head positioned 105 within the chamber of the wrench and pivotally mounted upon said pin and having teeth at its end, the edges of the handle pro-

vided with threads, a screw ring upon said threads, a pin upon the handle adapted to limit the movement of the ring in one direction, a second jaw and a shank portion moveable through the slot in the chambered jaw and having serrations upon one edge engaging the teeth upon the end of the handle.

In testimony whereof I hereunto affix my signature in presence of two witnesses.

CLARK E. SULLIVAN.
